US00D621295S

(12) **United States Design Patent**
Skalka

(10) **Patent No.:** **US D621,295 S**
(45) **Date of Patent:** ** *Aug. 10, 2010

(54) **PLANTER**

(75) Inventor: **Gerald Skalka**, Potomac, MD (US)

(73) Assignee: **Victor Stanley, Inc.**, Dunkirk, MD (US)

(*) Notice: This patent is subject to a terminal disclaimer.

(**) Term: **14 Years**

(21) Appl. No.: **29/290,322**

(22) Filed: **Nov. 19, 2007**
